UNITED STATES PATENT OFFICE.

ELLSWORTH A. HAWTHORNE, OF BRIDGEPORT, CONNECTICUT.

LAMP.

1,380,100.

Specification of Letters Patent. Patented May 31, 1921.

Application filed January 16, 1917. Serial No. 142,729.

To all whom it may concern:

Be it known that I, ELLSWORTH A. HAWTHORNE, a citizen of the United States, and a resident of Bridgeport, in the county of 5 Fairfield and State of Connecticut, have invented an Improvement in Lamps, of which the following description, in connection with the accompanying drawings, is a specification, like characters on the drawings representing like parts.

This invention relates to lamps, and is more particularly concerned with means for fastening parts of the lamp together in such a manner as to hold them securely, and 15 to facilitate assembling and dismounting them.

My invention will be best understood by reference to the following description, when taken in connection with the accompanying 20 drawings of one specific embodiment thereof, while its scope will be more particularly pointed out in the appended claims.

In the drawings:

Figure 1 is a central, longitudinal sectional view, partly in elevation, of a lamp embodying my invention;

Fig. 2 is a detail sectional view, on an enlarged scale, of a portion of Fig. 1;

Fig. 3 is a detail sectional view, on an enlarged scale, on line 3—3 of Fig. 1; and

Fig. 4 is a detail, sectional view, on an enlarged scale, on line 4—4 of Fig. 1.

Referring to the drawings, and to the embodiment of my invention which is selected 35 for illustration, I have there shown a lamp having a suitable principal light source, or light-producing means, herein in the form of an incandescent electric bulb 5, whose rays are suitably focused and projected by

40 one or more reflectors, herein a parabolic reflector 6, disposed at the rear of the main light source, and a spherical reflector 7, disposed forward of the main light source. Incidentally, this spherical reflector serves

45 also as a shield to limit the range of a supplemental light source, or light-producing means, herein in the form of an incandescent electric bulb 8. It is unnecessary herein to consider the manner in which these reflectors affect the light rays, since such feature forms the subject matter of an application, of another party. It will suffice to say that the light rays may be, and herein are, projected through suitable light-transmitting

50 means, herein in the form of a lens or glazing 9.

The lamp is provided with a suitable casing, herein comprising two parts 10 and 11. In the present instance, the part 10 constitutes the body of the casing, and the part 11 60 the bezel or door. The latter herein serves as a mounting or frame for the lens or glazing 9, and to that end, the front face of the latter is seated against a suitable seat 12, herein formed as a part of the bezel, the 65 glazing being held seated thereagainst by appropriate means, such for example as a retaining ring 13, whose periphery is seated in and interlocked with a grooved bead 14 provided in the bezel 11. 70

The body 10 and bezel 11 are herein telescoped, one upon the other, and one of them, herein the body 10, is provided with a seat 15, against which is seated a flange 16, formed on the reflector 6. This flange, in 75 turn, is provided with a seat 17 for a flange 18 formed on the reflector 7, the latter being herein centered with relation to the reflector 6 by a lip or shoulder 19, best shown in Fig. 2, formed on the flange 16, and encircling 80 the flange 18.

As a means for retaining the reflectors so seated one against the other, and such other against its seat in the casing, I have herein provided a retaining member in the form of 85 a ring 20, seated against the flange 18. This ring may be, and herein is, seated in a grooved bead 21 formed in the body 10 of the casing. This ring is preferably expansible and contractible, and is normally expanded so that part of its cross section enters the grooved bead 21, as best shown in Fig. 2. 90

As a means for holding the retaining member 20 in place, and for securing the 95 casing parts 10 and 11 together, I have provided suitable means, herein comprising a plurality of radial screws 22, extending through perforations 23 formed in a flange 24 on the bezel 11, and extending also 100 through bayonet slots 25 provided in a flange 26 on the body 10. The flanges 24 and 26 are mounted to turn and move axially one upon the other, so that the two casing parts may be locked together by first moving them 105 in an axial direction to introduce the screws 22 into the bayonet slots 25, and then turning the casing parts one upon the other in the proper direction to cause the screws to move circumferentially in their respective 110 bayonet slots as far as the latter will permit. This action will be readily understood by

an inspection of Fig. 4, which shows one of the bayonet slots with the screw therein.

Threaded on to the screws 22 are nuts 27, which serve a two-fold purpose. In the first place, these nuts hold their respective screws in place, and when tightened, clamp the casing parts together. In the second place, these nuts are utilized as a means for exerting pressure against the ring 20 in an axial direction against the flange 18, thereby holding the latter against its seat 17, and also holding the flange 16 against its seat 15.

This result is herein obtained by providing a nut having a corner 28, whose radius 15 (represented by the line A in Fig. 3) from the axis of the nut to such corner is slightly greater than the shortest distance from said axis to the ring 20. Assuming that the screw and nut are provided with right-hand 20 threads, when the screw is turned in the direction of the arrow B in Fig. 3 to tighten the same, the natural tendency is to turn the nut about its axis in the direction of said arrow. The corner 28, therefore, exerts a wedging action against the ring 20, thereby forcing the latter in an axial direction toward the seat 15. This will naturally tend to expand the ring radially into its bead, thus seating the ring firmly thereinto, 25 and seating the reflectors one against the other, and the latter against its seat in the casing.

Thus it will be seen that there is provided a single means which fastens the two 35 parts of the casing together, and fastens the reflectors therein. By simply loosening the screws 22 to the proper extent, yet without entirely unscrewing them, the casing parts may be separated by turning one upon 40 the other the required distance to bring the screws in line with the entrances of the bayonet slots, and then oppositely moving the casing parts axially to withdraw the screws from the bayonet slots. The parts 45 are re-assembled by simply reversing the foregoing operation.

While I have herein shown and described one specific form or embodiment of my invention for illustrative purposes, and have 50 disclosed and discussed in detail the construction and arrangement incidental to one specific application thereof, it is to be understood that the invention is limited neither to the mere details or relative arrangement 55 of parts, nor to its specific embodiment herein shown, but that extensive deviations from the illustrated form or embodiment of the invention may be made within the scope of the appended claims, without departing 60 from the principles thereof.

Having thus described my invention, what I claim and desire by Letters Patent to procure is:

1. In a lamp, the combination of a casing 65 in two parts, one telescoped within the other,

one being provided with a plurality of bayonet slots, and one being provided with a seat, a plurality of reflectors disposed within said casing, one of said reflectors being seated against the other, and such other reflector being seated against said seat, a retaining member for retaining said reflectors so seated, and means for holding said retaining member in place and for holding said casing parts together, said means including fastening elements located in said bayonet slots, respectively.

2. In a lamp, the combination of a casing comprising two parts, one telescoped within the other, one being provided with a plurality of openings, and one being provided with a seat, a reflector disposed within said casing and seated against said seat, and means for holding said reflector seated against said seat and for holding said casing parts together, said means comprising fastening elements extending through said openings to the exterior of said casing and being operable by movement relatively to both of said casing parts to urge said reflector against said seat.

3. In a lamp, the combination of a casing in two parts, one telescoped within the other, one being provided with a plurality of bayonet slots, and one being provided with a seat, a plurality of reflectors disposed within said casing, one of said reflectors being seated against the other, and such other reflector being seated against said seat, a retaining member for retaining said reflectors so seated, and means for holding said retaining member in place and for holding said casing parts together, said means including threaded elements extending through said bayonet slots, respectively.

4. In a lamp, the combination of a casing in two parts one telescoped within the other, one being provided with a plurality of slots, and one being provided with a seat, a reflector disposed within said casing and seated against said seat, and means for holding said reflector seated against said seat and for holding said casing parts together, said means including threaded elements extending from the exterior of said casing through 115 said slots, respectively and operable independently of relative movement of said casing parts.

5. In a lamp, the combination of a casing in two parts one telescoped within the other, one being provided with a plurality of bayonet slots, and one being provided with a seat, a plurality of reflectors disposed within said casing, one of said reflectors being seated against the other, and such other reflector being seated against said seat, a retaining member for retaining said reflectors so seated, and means for holding said retaining member in place and for holding said casing parts together, said means in-

- cluding screws extending through said bayonet slots, respectively, and nuts threaded onto said screws, respectively, and engaging said retaining member.
- 5 6. In a lamp, the combination of a casing in two parts one telescoped within the other, one being provided with a plurality of bayonet slots, and one being provided with a seat, a reflector disposed within said casing and seated against said seat, and means for holding said reflector seated against said seat and for holding said casing parts together, said means including screws extending through said bayonet slots, respectively, and nuts threaded onto said screws, respectively, and nuts, urging said reflector against said seat. 70
- 10 7. In a lamp, the combination of a casing in two parts one telescoped within the other, one being provided with a plurality of bayonet slots, and one being provided with a seat, a plurality of reflectors disposed within said casing, one of said reflectors being seated against the other, and such other reflector being seated against said seat, a retaining member for retaining said reflectors so seated, and means for holding said retaining member in place and for holding said casing parts together, said means including screws extending through said bayonet slots, respectively, and nuts threaded onto said screws, respectively, and having portions engaging said retaining member with a wedging action. 75
- 15 8. In a lamp, the combination of a casing in two parts, one being provided with a plurality of bayonet slots, and one being provided with a seat, a reflector disposed within said casing and seated against said seat, and means for holding said reflector seated against said seat and for holding said casing parts together, said means including screws extending through said bayonet slots, respectively, and nuts threaded onto said screws, respectively, and exerting a wedging action against said reflector to hold the latter against said seat. 80
- 20 9. In a lamp, the combination of a casing in two parts one telescoped within the other, one being provided with a plurality of bayonet slots and one being provided with a seat, a plurality of reflectors disposed within said casing, one of said reflectors having its marginal portion seated against the other, and such other reflector having its marginal portion seated against said seat, a retaining member for retaining said reflectors so seated, and means for holding said retaining member in place and for holding said casing parts together, said means including fastening elements located in said bayonet slots, respectively. 85
- 25 10. In a lamp, the combination of a casing comprising two parts, one telescoped within the other, each being provided with a plurality of openings, and one being provided with a seat, a reflector housed within said casing and having its marginal portion seated against said seat, and means for holding said marginal portion so seated and for holding said casing parts together, said means including screws extending from the exterior of said casing into said openings. 90
- 30 11. In a lamp, the combination of a casing in two parts, one provided with a generally L-shaped bayonet slot and one being provided with a seat, a reflector disposed within said casing and having its marginal portion seated against said seat, and means for urging said marginal portion in an axial direction against said seat and for holding said casing parts together, said means including a fastening element located in said bayonet slot and exerting an axial thrust against said reflector. 95
- 35 12. In a lamp, the combination of a casing in two parts, one provided with a seat, a reflector disposed within said casing and seated against said seat, and means for urging said reflector in an axial direction against said seat and for holding said casing parts together, said means including an element extending through said casing parts to the exterior of said casing and exerting an axial thrust against said reflector. 100
- 40 13. In a lamp, the combination of a casing provided with a plurality of openings, a reflector having a marginal portion seating in a rearward direction in said casing, and means to urge said reflector rearwardly against its seat, said means including a plurality of screws extending through said openings to the exterior of said casing and being operable by movement relatively to said casing to urge said reflector against said seat. 105
- 45 14. In a lamp, the combination of a casing in two parts, one of which presents a seat, a reflector within said casing and seated axially against said seat, and means for exerting a leverage action in an axial direction to secure said casing parts to each other and to urge said reflector against said seat, said means comprising an actuating element normally accessible and operable from the exterior of said casing. 110
- 50 15. In a lamp, the combination of a casing in two parts, a reflector, and means to secure said parts to each other, said means having provision for exerting holding pressures in an axial direction against said reflector and in a radial direction with relation to said casing. 115
- 55 16. In a lamp, the combination of a casing in two parts, a reflector, and means to secure said parts to each other, said means including a threaded member exerting holding pressures in an axial direction against 120
- 60 130

41
said reflector and in a radial direction with relation to said casing.

17. In a lamp, the combination of a casing in two parts, a reflector, and means to secure said parts to each other, said means including a radially disposed threaded member exerting holding pressures in an axial direction against said reflector and in a radial direction with relation to said casing.

10 18. In a lamp, the combination of a cas-

ing in two parts, a reflector, and means to secure said parts to each other, said means including a pair of coöperating radially disposed threaded members exerting holding pressures in an axial direction against said reflector and in a radial direction with relation to said casing. 15

In testimony whereof, I have signed my name to this specification.

ELLSWORTH A. HAWTHORNE.
